UNITED STATES PATENT OFFICE

2,485,302

TILTING MIXING MACHINE

Joseph C. Lukas, Dunellen, N. J., assignor, by
mesne assignments, to Worthington Pump and
Machinery Corporation, Harrison, N. J., a cor-
poration of Delaware

Application April 9, 1947, Serial No. 740,364

2 Claims. (Cl. 259—81)

1

This invention relates to mixing machines and, in particular, refers to the type in which the drum may be independently tilted and rotated.

The primary object of this invention is to provide an inexpensive yet highly versatile mixing unit in which a normally vertical mixing drum may be rotated and tilted either simultaneously or independently.

Another object is to provide a mixing machine in which the depth of the material being mixed can be varied without varying the angle of the tilt.

A further object is to provide novel means for introducing fluid into the interior of the drum.

This machine is particularly useful for mixing or coating ingredients in the food, candy, and drug industries. It may also be used to advantage for tumbling, burnishing, polishing, and allied operations requiring agitated movement of a quantity of discrete articles.

With these and other objects in view, as may appear from the accompanying specification, the invention consists of various features of construction and combination of parts, which will be first described in connection with the accompanying drawings, showing a tilting mixing machine of a preferred form embodying the invention, and the features forming the invention will be specifically pointed out in the claims.

In the drawings:

Figure 1 is an enlarged view, partly in section, taken along the line 1—1 of Figure 3 in which one segment gear and the driving gear therefor are removed from the device.

Figure 2 is a side elevation taken from the right of Figure 1.

Figure 3 is a side elevation taken from the left of Figure 1.

Figure 4 is a vertical section of a portion of a slightly modified form of the mixer showing the fluid feeding means.

Figure 5 is a side elevation partly in section showing the telescoping mixing drum.

Referring more particularly to the drawings, the improved mixing machine has a frame 1 with vertical side sections overhanging a base section. The laterally spaced coaxial bearing brackets 2 are attached to the upper terminal portions of the side sections to furnish a pivotal axis for the mixing vessel. Trunnion brackets 3 and 4 are bolted to a yoke member 5 and journaled into bearing brackets 2, as shown in Figure 1, to pivotally attach the yoke 5 to the frame 1.

2

The yoke 5 provides a normally vertical axis of rotation for the drum by means of its centrally disposed tubular bearing housing 6 with vertically spaced thrust bearings 7 and 8 therein and a lubricant chamber 9 which is sealed by suitable means at the bottom of the housing 6. The central cylindrical boss 10 of a circular table 11 is rotatably seated on bearing 7 in the upper portion of housing 6. Seated flush with the surface of the table 11 is a spindle 12 which extends through the boss 10 and the bearings 7 and 8. The lower end of the spindle 12 is threaded and has a nut 13 attached thereto abutting the bearing 8 to prevent vertical play or movement along the axis of rotation and to properly seat the table 11. The mixing drum 14, which may be of any desired construction, is removably attached to the table 11 by suitable means such as the bolts 15 extending through the top and/or the peripheral flange 16 of the table 11 and engaging lugs on the bottom of the drum or a flange thereon. The drum could obviously also be attached by various clamping schemes or by welding. The drum is provided with permanent or removable mixing blades (not shown) as is common in the art.

A ring bevel gear 17 is suitably attached to the flange 16 of the table and is driven by a pinion gear 18. The interior of the trunnion 4 has thrust bearings 19 and 20 and a lubricant chamber 21 for rotatably mounting the pinion 18 and a driving sprocket 22 which are keyed to a spindle 23 coaxial with the bearings 2.

Power for rotation of the table and drum 14 is transmitted by suitable means 24 from a motor 25 to the driving sprocket 22; from sprocket 22 through the spindle 23 to the pinion 18; and from pinion 18 to bevel gear 17 to the table 11.

The yoke, table, and drum are tilted by means of vertical segment gears 26 which are bolted to the sides of the yoke 5. To facilitate illustration only one such gear is shown in Figure 1, the other gear being attached in a similar manner on the opposite side and driven by a pinion 28 on the cross shaft 27. Power is transmitted to pinions 28 and the cross shaft 27 by the motor 29 through suitable transmission means 30 which include a worm and wheel or irreversible gearing 31 to prevent tilting due to the weight of the drum. The pinions 28 engage the segment gears 26 and by rotating them cause tilting of the yoke 5, and attached members, about the horizontal axis of the bearing brackets 2. The segment gears 26 have adjustable stops 32 fixed on their sides 55 which engage suitable stops (not shown) on the

frame to limit the degree to which the unit may be tilted.

Since the pinion 18 for rotating the drum is coaxial with the axis about which the drum pivots, it is apparent that it may be rotated regardless of its tilt. This feature makes it possible to provide common electrical controls associated with the stops 32 and motors 25 and 29 to automatically tilt the drum while it is rotating. By varying the speed of tilting and speed of rotation, the agitated motion of the articles within the drum may be altered. In the drawings, however, the controls for each motor are simply the switches 33 and 34 so that tilting is manually controlled.

The motors 25 and 29 as well as transmission means 24 and 30 and cross shaft 27 may be easily mounted by conventional methods on the frame 1. While two motors are preferred, it is apparent that one motor could be employed to furnish power for tilting and rotating the drum 14 by a rearrangement of the power transmission means 24 and 30.

The embodiment of Figures 4 and 5 has exactly the same rotating and tilting means as that of Figures 1 to 3. However, this embodiment also includes fluid feeding means and a telescopic mixing drum.

The fluid feeding means includes a spray pipe or tubular conduit 40 which is mounted inside the hollow spindle 12a. The pipe 40 is of substantial length and extends through opening 42 well up into the drum 50 as shown in Figure 5. The packing 41 prevents reverse flow of fluid from the drum through opening 42. The packing 41 and the nut 13a fit tightly around the pipe so as to inhibit undesired sliding movement; though by loosening them the pipe can be withdrawn from or further inserted into the drum. The nut 13a performs the same function with respect to the spindle 12a as the nut 13 previously described and the spindle 12a is mounted in the bearing housing 6 in the same manner as illustrated and described in connection with Figure 1. Other equivalent means may of course be used to prevent sliding of the pipe 40.

The spray pipe 40 extends out through the bottom of the spindle 12a and housing 6 where it is coupled at 43 to a flexible hose 44. The coupling 43 is of a conventional type which permits relative rotation of the hose 44 and the pipe 40, since, in this embodiment, the pipe rotates with the drum 50 while the hose 44 is not rotatable. It is to be understood, of course, that this feature could be modified so that the pipe is stationary by the common expedient of inserting bearings between the pipe and the rotatable spindle 12a and drum 50.

As indicated in Figure 5 the flexible hose permits tilting of the drum and spray pipe 40 while at the same time connecting the pipe to a source of fluid (not shown). The hose 44 is of sufficient length to permit the desired arc of tilting. The spray pipe 40 has a closed end 45 so that the fluid is forced out through a multiplicity of perforations 46 in the wall of that portion of the pipe 40 which is inside of the drum 50.

The telescopic drum 50 is made up of three concentric annular shells 51, 52, and 53 which slip one inside the other. The bottom shell 51 is adapted in the same manner as drum 14 for attachment to the table 11. The intermediate shell 52 is substantially cylindrical and the upper shell 53 is substantially frustro-conical having a mouth or charging and discharging opening 54.

Each of the shells have radially extending annular flanges 55 so arranged that when the drum is collapsed or only partially extended they may be bolted together as at 56. The shells are held in their extended or partially extended positions by means of bolts, as shown at 57, which join the cylindrical walls through mating holes therein.

It is obvious that the drum can be made of any desired number of concentric shells and that they can be so constructed and arranged that the innermost shell 51 is of the smallest diameter rather than the largest diameter as shown.

The telescopic drum 50 makes it possible to vary the pressure on articles 58 within the drum. By extending the drum the depth of a given quantity of articles 58 will be reduced when the drum is tilted, hence the pressure on the articles will be reduced. In treating soft articles such as candies this feature is particularly advantageous since it eliminates crushing of the articles at the bottom due to the weight of those above.

The hose 44 and spray pipe 40 may be used to supply various fluids to the drum. For example, refrigerated air for cooling purposes or hardenable syrup for coating candies may be pumped into the drum; or fine sand may be blown into the drum for blasting and cleaning metal articles. In the latter case, of course, the wear resistance of the pipe 40 would have to be increased by suitable inserts in the holes 46. The telescopic drum facilitates cooling and other operations by providing a greater surface area of the mass of articles. In the event that different fluids are required at various intervals during the processing of articles within the drum, the supply of fluids can be controlled by means of a suitable valve (not shown) as is common knowledge.

It is to be understood that the specific construction recited heretofore may be widely modified within the spirit of the invention defined by the appended claims.

What is claimed is:

1. In a mixing machine, a supporting frame, a yoke pivotally carried by said frame for pivotal movement on a horizontal axis, a tubular bearing housing carried by said yoke, bearings in said bearing housing, a vertical spindle rotatably supported by said bearings for rotation about a vertical axis, a circular table carried by the upper end of said spindle, a depending annular flange on said circular table, a mixing drum, a depending annular flange on said mixing drum and engaging about said table carried flange, means connecting said table to said drum carried flange, a ring gear carried by said table carried flange, and means connected to said ring gear for rotating said drum about a vertical axis.

2. In a mixing machine, a supporting frame, a yoke pivotally carried by said frame for pivotal movement on a horizontal axis, a tubular bearing housing carried by said yoke, bearings in said bearing housing, a vertical spindle rotatably supported by said bearings for rotation about a vertical axis, a circular table carried by the upper end of said spindle, a depending annular flange on said circular table, a mixing drum, a depending annular flange on said mixing drum and engaging about said table carried flange, means connecting said table to said drum carried flange, a ring gear carried by said table carried flange, a motor carried by said frame, power transmitting means connecting said motor to said ring gear for rotating said drum, a second motor carried by said frame, and power transmitting means

connecting said second motor and said yoke for tilting the yoke and drum on the pivotal axis of the yoke.

JOSEPH C. LUKAS.
